PRINTING APPARATUS FOR LENTICULATED FILMS

Kurt Räntsche, Berlin-Teltow, Germany, assignor to Opticolor, Aktiengesellschaft, Glarus, Switzerland, a corporation of Switzerland

Application September 8, 1933, Serial No. 688,545
In Germany December 23, 1932

26 Claims. (CL 88—24)

This invention relates to printing machines for lenticulated films. More particularly it relates to the type of optical printing machines which are characterized by the fact that the original is imaged by a lens or lens system on the copy. Thus all advantages of optical printing machines as compared with contact printing machines are brought into effect. The chief of these advantages are:

10 Diaphragms or masks, impermeable to light, may be arranged at those spots where the zones of the multicolor filter of the taking or projecting process are adjacent, so that the effect of light diffusion in the photographic layer is reduced and the purity of colors is augmented.

Further, sharper images may be got, taking into account, that the light which passed through one lenticular element of an original lenticulated film is spread over several lenses of 20 a copying lenticulated film, and that the number of these lenses is smaller with optical printing than with contact printing.

Another advantage characterizing the invention is, that all difficulties resulting from being obliged to employ lenses with great aperture, are avoided. Supposing that the angular openings of the camera and projection lenses are equal to the angular opening of the lenticular elements, which is generally about 1:2.5, the printing lens 30 too must be seen from the films at an angular opening of about 1:2.5.

This requires the aperture "f:1.25" of the printing-lens, when the sizes of the images on the original and copy films are to be the same. 35 On the other hand, the definition of the image must be so good as to render only diffusion circles which are smaller than the lenticular elements. Till now, lenses of the aforesaid qualities could not be made.

40 The invention makes it possible to get optical copies by employing a lens of smaller opening than those of the taking or projecting process. By suitably chosen means the lens opening is seen from the film in different directions, so that the lens is as effective as one with great opening. The means may be fixed or movably arranged. They may be plane mirrors, arranged in such a manner that images of the lens are seen from the films as if at the sides of the lens 45 itself. Such an arrangement is advantageous regarding the mechanical construction, but from the optical point of view it is more preferable to employ movable means, as they make it possible to get better images.

55 The fundamental idea of the invention is to

employ a lens with small opening and a great well corrected image field instead of a lens with great opening and only a small image field, as the first named lens may be obtained much more easily.

The principle of the invention and some machines of the new type will be explained by the help of the drawings.

Figs. 1 and 2 show the principle upon which those of the new machines which contain fixed means are based.

Fig. 3 is a sectional view of a copying device, a detail being represented by Fig. 4.

Figs. 5 and 6 as well as Figs. 7 and 8 are two sectional views of other devices.

Fig. 9 is a diagram illustrating a slight modification.

Fig. 10 is a diagrammatic showing of means for getting three different copies on smooth films from one film with lenticular elements.

Fig. 11 is a plan view of an arrangement with movably arranged means.

Figs. 12, 12' and 12'' show three different positions of a machine with movable optical means.

Fig. 13 is a front view of such a machine.

Figs. 14 and 18 serve for explaining the manner of operating of a machine which is represented by

Fig. 15 in plan-view, by Fig. 16 in front-view, and by Fig. 17 in a vertical section on the line 17—17 of Fig. 15.

Some modifications of that machine are explained by the help of Figs. 19 through 23.

Fig. 24 is a plan-view of another device.

Fig. 25 representing a detail of the device shown in Fig. 24.

Referring first to Fig. 1, the cylindrical lenticulations of the film 1 face the lens 2. There is only drawn the path of light rays on one side of the lens 2, as it is just the same on the other side. 40 Plane mirrors 3 and 4 are arranged by the side of the lens and in parallel to its optical axis as well as to the cylindrical elements. Their reflecting sides face each other, so that, from the film 1, an infinite number of images of the objective may be seen. Some of these images are designated by 2', 2'', 2''' and 2 (IV), though in most cases only the images 2' and 2'' need be considered.

Now it may be assumed that the angular opening of a lenticular element is equal to the angle by which the images of the lens from 2''' to 2 (IV), including the lens itself, are seen. When the film is lighted from its smooth side, part of the light passing through one lenticular element,

reaches directly the lens 2, other parts not before being reflected by the mirrors 3 and 4. That part of light passing immediately from the film 1 to the lens 2 is confined within the angle a . Another part which is reflected by the mirror 4 and then passes through the lens is confined within the angle b , which is defined by drawing straight lines from a point of the film to the edges of the image 2'. Further, the angle c , defined by the straight lines from the same point of the film to the edges of the image 2'', is filled by that part of the light, which is first reflected by the mirror 4 and then by the mirror 3, before reaching the lens.

15. The light beams, which leave the film in the directions of the images 2'', and 2 (IV), are in a corresponding manner reflected, before passing through the lens.

Thus the light beams emerging from the film partly meet the lens directly, partly after reflection by the mirrors 3 and 4. The reflected light beams pass inclined through the lens as if they had started from the virtual film-images 1' through 1 (IV) which are seen from the lens in the mirrors. Consequently, by the employment of the mirrors 3 and 4, the image field, taken by the lens and imaged without aberrations, is increased by the same ratio as the real lens-aperture is decreased.

30. When, on the other side of the lens 2, corresponding mirrors and the printing or copy film are arranged, the light beams there follow similar paths, whereby it is also possible to get images greater or smaller than the original.

35. The openings seen from the film are drawn in Fig. 2. From this figure it may be seen, that the height of the real and virtual lens openings is varying, being zero where two openings are adjacent. In order to avoid this, only rectangularly shaped openings may be used. But it is also possible that, when filter zones of equal width are used, the borders between two openings are seen from the films in those directions where the borders between two filter zones are seen in the taking or projecting process, so that, by the diminution of height, a shading of the parts corresponding to the borders of the filter zones is effected.

40. As is well known in the art, pictures are taken on the original film through a filter having zones of different colors, thus forming a group of color records in the emulsion behind each lenticulation of the original or exposed film.

45. As, generally, a filter is used which is made up of filter zones of only three colors, it is preferable to use a copying lens with a relative opening of about one third of that of the lenticular elements, so that only the images 2' and 2'' are employed. All rays emerging from the film pass through the lens, either immediately or after being only once reflected.

50. A copying device based upon the said principles is represented in Figure 3. The original film 1 is lighted by the light source 5 and the condenser 6. Near the film 1 between the film and the lens 2 is arranged a lens 7 which causes the lens openings to be seen at the same distance as the filter was seen in the taking process. When, for instance, the filter was collimated and therefore seen in infinity, the focal length of the lens 7 may be equal to its distance from the diaphragm 8.

55. Assuming the relative opening of the lenticular elements to be 1:2.5 and the filter to be made up of three zones of equal width, the copying lens 75 may have an opening of "f:3.75", as then it is seen

from the films by an angle of 1:7.5. This is one third of that angle by which the light rays are emerging from the film 1.

The diaphragm 8 is placed in the interior of the lens system 2. It cuts the lateral margins 5 of the lens opening, which has the shape represented in Figure 4. Those zones of the opening corresponding to the borders between two filter zones are shaded. The lens opening 9 corresponds to the middle zone. Its images 10 and 11 10 correspond to the lateral zones. The width by which the openings are seen from the film may be equal to the width by which the corresponding filter zones are seen in the taking or projecting process.

15. In Figure 4 the light beams which pass through a point at the margin of the original film are drawn. The three angles marked by single circles correspond to the three filter zones. The rays contained in these angles reach the lens 2 either immediately or after reflection by the mirrors 3 and 4, while those rays contained in the angles between the arcs and chords of the various circles are cut off by the diaphragm 8. The way of the light beams on the side of the printing film 13 corresponds wholly to that on the other side. There are the mirrors 3' and 4' and the lens 12.

There may arise a difficulty from the fact that the lens or lens-system 2 must be exactly symmetrical in both directions. To get such a system, two taking objectives of the same type may be combined. But there are nearly always small differences between two such objectives, so that the definition of the image is not the best.

30. Therefore, in order to simplify the device and to improve it, a plane mirror may be arranged in the plane of the diaphragm 8. Besides, the two films are arranged on the same side of the lens 2, one somewhat above, the other somewhat 40 beneath the optical axis, so that the light rays pass through the same optical system on their way to and fro. As, on the other hand, as was told already, the lens 2 images a relatively large field, without aberrations or other faults, there 45 results no difficulty from arranging the films at a distance from the optical axis.

50. Besides the arrangement of Figure 3 may have the drawback, that not only the required number of lens-images are effective, but that their number is really infinite. So there is light incident on the printing film which is very inclined as if there were more filter zones than in the taking or projecting process. This light has passed the lens under such an angle which is greater than 55 the angle of the well corrected image field. This drawback may be avoided by arranging diaphragms or similarly acting means near the path of light rays, so that only a small number of lens images may be seen from the films, those 60 light beams being cut off which else give rise to the rest of the lens images.

65. A device is drawn in Figures 5 and 6, which is constructed so that both films are on the same side of the lens, behind which a plane mirror is arranged, and that disturbing reflected light is cut off by diaphragms.

The film 1 and the lens 2 are arranged so that, from the film, lens images may be seen in the mirrors 3 and 4. The lens aperture seen from the film is marked by the double arrow 15. From the film the images 15' and 15'' are seen by the sides of 15. The light passing through the film 1 reaches the lens 2 either immediately or after reflection by the mirrors 3 and 4. A plane 75

or curved mirror 6 is arranged behind the lens 2. It reflects the light so that it returns back to the printing film 13, passing thereby the lens 2 and the mirrors 3 and 4. The original and 5 the printing film are somewhat distant from the optical axis in a direction parallel to the cylindrical, lenticular elements, as is seen from Figure 6.

In order to prevent such light, being several 10 times reflected by the mirrors 3 and 4, from reaching the lens-opening 5 and the printing film 13, the diaphragms 17 and 18 are arranged in such a way that the aperture 15 and only the images 15' and 15'' but no further images may 15 be seen from the films. The diaphragms 17 and 18 have their directions determined by lines connecting the right margin of the lens with the right margin of the image on the film and correspondingly connecting the left margins of the 20 film and lens, respectively.

Besides, the mirrors 3 and 4 are only as great as is necessary for producing complete images 15' and 15'' for all points of the images on the films.

25 If there seems, at first sight, to be no possibility of arranging diaphragms or similar means, which cut off the disturbing reflected but not the useful light, the aperture of the lens 2 may be decreased and its distance from the film increased, 30 so that the places for the diaphragms are obtained. Such a decreasing of the lens aperture does not affect in any disturbing way the printed images, as, when printing, it is necessary for getting good copies, to image only a small part 35 of each stripe of the original film's photographic layer on to the printing film, the said stripes being the images of the filter zones. In the device represented by the Figures 5 and 6 the aperture 15 is imaged by the lenticular elements about on 40 the center of the stripe, which corresponds to the central filter zone, the images 15' and 15'' being images on the centers of the stripes, which correspond to the marginal filter zones.

When the lens aperture is varied, it is also 45 necessary to vary the situation and size of the diaphragms. Such diaphragms are, as may easily be seen, also of great advantage with devices according to Figure 3, in order to improve the printed images.

50 The device according to Figure 3 may be further improved by arranging a glass-block between the film and the lens. This block has two plane and parallel surfaces, which are effective as the mirrors 3 and 4, either by being coated with a 55 reflecting layer or in consequence of total reflection. The lens 7 may be cut of the same piece as the block or may be cemented to it.

The first lens of the objective may also be 60 cemented to the block. By these means it is possible to copy with small losses of light, as the reflection at the plane surfaces is very good and as there are only a few optically active surfaces between glass and air. At last the relative aperture of the lens may be smaller by a ratio equal 65 to the refractive-index of the glass, as the lens is arranged between glass instead of air.

A device combining several of the told advantages is shown in the Figures 7 and 8 in vertical 70 and horizontal sectional view.

In Figure 7 the original film 1 is arranged under and the copying film over a glass-block 14. This block carries at its end a concave mirror 28 and is cut at the opposite side like a swallow-tail. There are the reflecting surfaces 26 and 27.

Under and over these surfaces are the lenses 7 and 12 near the films. By reflexion at the mirrors 26 and 28 the film images 21 and 22 are generated. These are lying one close over the other, so that the optical axis of the mirror 28 5 may pass between them.

In Figure 8, the surfaces 26 and 27 are omitted and the block is drawn as if it had the shape which it has virtually by the reflexion at the mirrors 26 and 27. 10

Then the lens 7 refracts the light beams so that the mirror 28 seems to have the same distance from the film as the multicolor screen of the camera. The light-beams emerging from the film 21 reach in the same manner as in the device 15 of Figure 3 partly the mirror 28 immediately and partly after reflection at the surfaces 23 and 24. The images of the mirror 28, seen in the mirrors 24 and 25, are designed by 28' and 28''. 20

An advantage of the described device is that 25 the losses of light are very small, as the light only once enters and once leaves the block and passes no other surfaces between glass and air. Besides, the images are nearly without any dispersion. At last, the relative aperture of the 30 mirror may be very small. For, assuming the relative aperture of the lenticular elements to be 1:2.5 and the camera screen to be formed by three zones of equal width, the light-beam which corresponds to one filter zone has an angular opening, when leaving the film, of 1:7.5. Taking into account that there are masks at the lateral margins of the mirror, the effective opening is only 1:9, and taking further into account that the mirror is effective in glass, the opening is reduced at last to 1:13.5. 35

Though concave mirrors of so small an aperture may be employed without any correction of spherical aberrations, the curvature of their image field is generally too considerable as to be 40 employed without further improvements. Therefore, it is preferable to replace the mirror by an optical system, consisting, for instance, of two or three separate lenses and a mirror behind them. 45

The lenses may be cemented ones, as is well known in the art, and may be corrected with respect to all aberrations or other faults. The mirror may be curved or plane.

As generally the glass block is rather long it 50 may be replaced by the block, represented in Figure 9. This block is shorter and broader and one of its front faces reflects the light so that it must run through the block several times. Figure 9 corresponds to Figure 7 and the details of 55 this device may be understood without further explanation.

It is preferable to employ with the new machines such light sources, for instance mercury arc-tubes, which only radiate light of a small 60 spectral region. It may have a spectrum of discrete lines, of which only one or some are employed. Then it is necessary to correct the optical means only for the employed light waves, from which results a considerable simplification. 65

There is still a way of compensating for a small curvature of the image field by slightly inclining the mirrors 23 and 24 with respect to each other, so that their planes are passing through the center of the image-sphere. Then too, the mirrors must, of course, be arranged so that they have the lens-aperture between them and that their intersections with the plane of the diaphragm run parallel to the cylindrically shaped lenticular elements. 70 75

One property of the device according to Figure 7, which is of special importance, is that the printed images are correct with respect to their right and left hand side. Thus the duplicate 5 copies may be projected with filters at the side of the objective, and it is not necessary to interchange right and left in the camera or in the projection apparatus. If a duplicate with inverted 10 sides should be needed, one of the reflecting surfaces 15 faces 26 or 27 must be omitted and one film must be arranged, where in Figure 7 one of the film images 21 or 22 is generated by the mirror 26 or 27.

With respect to Figure 5 it was already told 15 that the disturbing light which is severally reflected may be—at least partly—suppressed by suitably limiting the mirrors 3 and 4. When a glass block is employed the limits of the reflecting surfaces may be given by the fact that only 20 such light which is incident under a rather small angle is totally reflected, but that the light which is incident nearly perpendicularly to the surface passes freely. The angle of total reflection 25 may be varied by suitably choosing the material of the glass block and by putting it into a medium of favorable refractive index, for instance oil or any other similar means.

It is important, that it is not necessary to employ an entire number of reflected lens openings. It may be sometimes preferable to employ only fractions of the outer images. Such a device is, for instance, of use, when a film must be copied, which was taken with a filter, the central zone being much smaller than the marginal zones. 30 Then, the real aperture of the lens is chosen, in such a way, that it is seen from the film by the same angle as the central zone of the taking screen. For copying one marginal zone, one and a half virtual lens images may for instance be 35 employed.

The new devices may also be important, when the relative aperture of the lens itself is equal to the relative aperture of a lenticular element. This is the case, when a film with very small 40 lenticular elements is used, so that each element photographs also filter images at those stripes of the layer behind the neighbouring elements. The filter, in this case, consists of more than three zones, the colours being periodically repeated. The relative aperture of the lens of the 45 printing device is equal to the relative aperture of the lenticular elements and the virtual images of said lens, seen in the mirrors 3 and 4, correspond to the periodically repeated marginal filter zones.

The new devices may also be employed for printing films with spherical lenticular elements which may be of circular, hexagonal, quadratic or other shape. Then virtual lens images are not 50 only generated at the sides of the real lens, but also above and beneath it, by arranging two further plane mirrors, so that the vertical section view is identical with the horizontal section view of Figure 3. There may be also six mirrors arranged, which intersect the plane of the lens diaphragm in a regular hexagon.

The idea of virtually increasing the lens aperture may also be brought into effect with devices for taking or projecting. Further, it is not restricted to color-cinematography, but may also be made use of with stereoscopic films, sound films, trick films and so on. At last, it is helpful when the images corresponding to different colors and combined on one lenticular film are 5 copied on separate smooth films or when images

on separate films are combined on one lenticular film.

A device which serves for the last mentioned purposes is shown in Figure 10. The lenticular film 1, the lens 2 and mirrors 3 and 4 are arranged exactly in the same manner as is represented in Figure 3. On the other side of the lens 2, a smooth film 25 is arranged at the same distance from the lens as the lenticular film 1. The image registered by the lenticular film and 10 corresponding to the centre of the taking screen is copied on the film 25.

The images corresponding to the marginal zones are copied on the films 25' and 25" which are arranged by the sides of the film 25. Preferably the films 1, 25, 25' and 25" are commonly transported. There may also be used only one 15 duplicate film of threefold width and, after the images being colored, this film may be folded so that the images register with each other.

In the before described devices only fixed means are employed for increasing virtually the aperture of the printing lens. But it is often better to employ movable means, so that the aperture is successively seen in different directions.

For this purpose the relative aperture of the real lens may be equal to the relative aperture of one filter zone or even less, always only the dimensions of the apertures in such sections, 30 which are perpendicular to the cylindrical lenses, being taken into account. After the central image is copied with such a lens, the films are moved in opposite directions so that the lens is seen from the films where one marginal filter 35 zone is seen in the taking or projecting process. At last in the same manner the image corresponding to the other marginal filter zone is copied (Figure 11).

Instead of moving the films, also optical means 40 may be moved. For this purpose suitable mirrors, for instance reflecting corners or totally reflecting prisms may be arranged and moved so that the lens is seen successively in different directions. Such devices are represented in the 45 Figures 12 through 25.

The film 1 of Figure 11 is supposed to have been exposed by a camera lens with a relative opening equal to that of the lenticular elements. If these elements are cylindrically shaped, only 50 a section perpendicular to the cylinder axes is considered. The multicolor screen of the camera lens may have consisted of three zones of equal width, so that there are three stripes of equal width behind each lenticular element, the said 55 stripes being the images of the zones and being equally or differently transparent.

It is without any influence, if the screen was placed near the diaphragm of the camera lens or if the screen was distant from the diaphragm, 60 so that from all points of the film gate other parts of the screen were seen, the screen consisting of more than three zones and the three colors being periodically repeated. In any case, there are three stripes behind each lenticular element, 65 which are the images of the filter zones, and the relative situation of the images and the elements defines the situation of the printing lens and of its images. Only when the distance, in which the printing lens is seen from the film is equal to 70 the distance, in which taking screen was seen, correct projection of all colors is possible.

The aperture of the lens 2 is given by the diaphragm 8. Its angular opening is equal to that of the central filter zone or even less. The copy- 75

ing process may be performed in three steps. At first the film 1 is lighted in that position which is shown in Figure 11 by closed lines, thus photographing the stripes corresponding to the central zone only. In order to copy the other stripes, the box 35, which contains the light source, the guiding and transport mechanism of the film 1, is slidably mounted on the shaft 36. By moving the box 35, the film 1 is carried to the position indicated by 1'. Synchronously the box 37, containing the guides and the transport mechanism of the film 13 is moved on the shaft 38, so that the film 13 is carried to the position indicated by 13'. In these positions the lens is seen from the films slantwise by the side of its former position. After exposing the films in this position, the boxes are moved to the other side, so that the films are then exposed in the positions 1'' and 13''. In the lateral positions 1', 13' and 1'', 13'' respectively the stripes corresponding to the marginal filter zones are copied.

The principle of the described device may also be explained by assuming the film 1 to be fixed and the lens 2 as well as the film 13 to be movable. Then, from the film 1, the lens 2 is seen successively at 2, 2' and 2''. The successively seen lens openings are not close to each other, but there are distances between them, so that only the light-rays within the angles marked by double-arcs are employed for the copying process. By this means the light-beams, which else would photograph the zones corresponding to the borders between two filter zones, are cut off.

The device is driven from the shaft 39. By the bevel-wheels 40 and 41 the shafts 36 and 38 are driven, upon which the boxes 35 and 37 are slidably mounted. They are moved by the lever 42, which turns round the axis 43 and is driven by the eccentric 44. The shutter, turning before the lens, is not drawn. The printing process goes on in the following manner: At first is printed in the position 1' and 13'. Then the shutter closes the lens aperture, the films are moved to 1 and 13 and the lens aperture is opened. Afterwards, when the shutter has closed once more the opening, the films are moved to 1'' and 13'', where the last exposing is performed. Then the shutter closes the lens-aperture, the transport mechanism within the boxes pulls the films onward by the height of a film-image, so that the next image may be printed. There are three new successive exposures in the positions 1'', 13'' and 1, 13 and 1', 13'. Then the films are pulled onward and the copying process begins once more.

This machine as well as those which will be described later on may be also employed in a somewhat different but more simple manner. A diaphragm may be put into the lens system, which has only a small opening, either slit- or point-shaped. The slit must be placed in parallel to the cylindrical lenticular elements. Then, the films being fixed, the boxes are continuously moved from the positions 1', 13' over 1, 13 to 1'', 13'' while the small aperture is open. Then the shutter closes the aperture, the films are pulled onward, and the boxes swing back, thereby copying the next image. In this manner all parts of the photographic layer lying behind one lenticular element are successively exposed. In order not to expose those parts which correspond to the borders between two adjacent filter zones, the shutter may have the shape represented in Figure 25.

The shutter 68 has three openings 74, 75 and 76. The closed parts 72 and 73 interrupt the

light, when the borders between the filter zones would be exposed, while the openings 74, 75 and 76 let the light pass when the position of the films allows the lens aperture to be seen in a direction contained within one of the angles marked by double arcs. The part 71 of the shutter closes the lens aperture, while the films are pulled onward. Sometimes, it may be preferable to limit the apertures 74, 75, 76 by curved edges as is represented by the lines 77 and 78 which would replace the edges 77' and 78'. By such a shape of the shutter-openings the diffusion of the light in the photographic layer may favorably be influenced.

For the illustration the described printing process may serve the Figure 18. As abscissa the time and as ordinate the position of the box 35 on the shaft 36 is chosen. By hatching those intervals are marked, during which the shutter cuts the light off. During the intervals 79, 79', 79'' and so on, the films are pulled onward, while the intervals 80, 81, 80', 81' and so on correspond to the positions, when the images of the filter-borders would be copied.

A slight modification is given by fixing the box 35 and moving the lens 2 as well as the box 37.

An important improvement is performed by arranging movable optical means between the films and the lens, so that these may remain fixed during the printing of one complete film-image. The principle is explained by the help of the Figures 12, 12' and 12''. The films are indicated by the arrows 1 and 13, in order to demonstrate, if the right and left hand sides are interchanged on the duplicate compared with the original. The arrows are in all figures of this specification shown in such a way that the top of one arrow is imaged by the objective and the other optical means on the top of the other arrow.

The film 1 is lighted by the light source 5 from the smooth side. The beams pass through the photographic layer, through the lenticular elements and reach the optical square, consisting of the two plane mirrors 46 and 47. The edge between the two mirrors, which are perpendicular to each other, is perpendicular to the plane of the drawings and parallel to the cylindrical elements on the films 1 and 13. The light beams pass the lens 2, the optical square, which is composed by the plane mirrors 48 and 49 and meet the duplicate film. The edge of the square 48, 49 too is parallel to the cylindrical elements.

The optical squares have the effect that, in the position of Figure 12, the films are seen from the lens 2 at 51 and 54 respectively. On the other hand the lens 2 is seen from the films at 52 and 53 respectively. The lens may have a relative aperture which is equal to the relative aperture of one filter-zone or even smaller.

While one film image is copied, the squares are moved parallel to themselves into the positions of the Figures 12' and 12''. In these figures all movable or moving parts of the device are designed by the same numbers respectively marked with one or two dashes.

As the distances between 1 and 52 and between 13 and 53 are equal to the distances between the films and the images of the multicolor screens in the taking or projecting process, the three positions may serve for copying the three parts of the image, which correspond to the differently colored filter zones. In each position one of the stripes behind each lenticular element is copied. But when the lens-aperture is small enough the

squares may also oscillate continuously, the exposure being interrupted, when the films are pulled onward.

5 There is no difference, if there are only two or more than three different stripes on the part of the layer behind one lenticular element, when the squares are continuously moved. When they are moved intermittently, the number of the positions, where they are at rest during the copying 10 of one film image, must be equal to the number of the said stripes, which number must not necessarily be equal to the number of different filter-zones. In each position one stripe is copied.

As the arrows 1 and 13 are turned in opposite directions, the images on the duplicates are false with respect to the left and right hand sides. If correct duplicates are desired, it is necessary to put still a plane mirror in the path of light rays.

20. The turn of the different positions, the driving mechanism for pulling the films and for making the squares to oscillate is similarly made as was drawn in Fig. 11. Besides, what was told about the shutter is also correct with respect to Figures 12, 12', and 12''.

A device which is based upon the same optical principles, but is preferable with respect to its mechanical construction is shown in Figure 13 in front-view. The images 1 and 13, which are copied (or produced by copying) are on the films 55 and 56. Between them is the lens 2. Optical squares 46, 47 and 48, 49 are arranged exactly in the same manner as is drawn in Figure 12. Two other squares 46'', 47'' and 48'', 49'' are arranged over the first-named squares and in fixed relation to them. At last there are still the squares 46', 47' and 48', 49' under the squares 46, 47 and 48, 49, which are also firmly connected to them. The squares are somewhat displaced one with respect to the other and movable in vertical direction, which will say: parallel to the direction of the films.

When they are moved downwards by the distance h , the squares 46'', 47'' and 48'', 49'' take the position drawn in Fig. 12''. When they are moved upwards by the distance h , the squares 46', 47' and 48', 49' take the position drawn in Fig. 12'. During the moving of the squares, the lens aperture is closed. It is only opened when the squares are at rest. By diaphragms that light is cut off, which would pass the wrong mirrors, and only those are free which are at the same height as the lens. In each of the three positions one stripe is copied and then the films are pulled onward. The advantage of this device is that all squares are in fixed relation to each other, so that there is only one moving member.

In order to get images which are correct with respect to the right and left hand side, three of the mirrors, for instance 46, 46', 46'', may be replaced each by a further optical square, the edges of these squares being perpendicular to the mirrors 47, 47' and 47''.

65 In order to avoid any discontinuity of movement, the mirrors 46, 46', 46'', 47 . . . and so on may be made much higher. Then they may slowly oscillate up and down, the exposure being interrupted, when one square replaces the other in the path of light rays or when the direction of the movement is changed and, synchronously, the films are pulled.

The mirrors and squares of the described device as well as of all other devices, which are examples of the invention may be formed by

totally reflecting prisms or by plates of any material with highly reflecting surfaces. Further, the stage-wise arrangement of the squares, represented by Figure 13 may be used with nearly all other devices.

Such another device is explained by Figure 14. There are the films 1 and 13, the fixed mirrors or prisms 58 and 59 with the lens 2 between them, and the movable optical squares or prisms 57 and 60, which are firmly connected with each other. They may oscillate, so that they may take the positions indicated by I, II and III. The light starts from 1, passes successively 57, 58, 2, 59, 60 and reaches 13. The images of the lens 2, seen from the films 1 or 13, in the three positions I, II and III are indicated by 62 or 62' respectively. From the lens 2, the films are seen at 63 and 64.

The fundamental principle of this device as well as of all others is that a lens of small aperture is successively—or synchronously—seen from the films in different directions and that in each moment both films are seen from the lens in exactly opposite directions. 20

The marginal stripes may be copied in the 23 positions I and III, the central stripe in the position II. They may be printed with intermittent or with continuous movement. The exposure may be interrupted when it passes from one stripe on the layer to the next one. There may also be made use of a stage-wise arrangement of the mirrors. 30

A machine which is based on the principle of Figure 14 is represented by the Figures 15, 16 and 17. Fig. 15 is a plan-view, Fig. 16 a front-view and Fig. 17 a sectional-view according to the line [7—11] of Fig. 15.

The films 55 and 56 are leaded by the guidings 101 and 102 which are fastened to the plate 97. 40 The images 1 and 13 are in front of the gates 111 and 112. The plate 97 is mounted on the base-plate 106. It carries the pull down mechanisms 103 and 104, which are driven by the shaft 98. The shaft 93 is related to 98 by the bevel- 45 wheels 92.

The plate 97 is fastened to the support 96 which serves as guiding for the sliding-carriage 107. Besides it carries the mirrors 87 and 88 and the lens-system 2. The carriage 107 carries the optical square 83, the optical cube 84 and the diaphragm 85. It is driven by the arm 95 and the eccentric 94 connected to the shaft 93.

A wheel 91 is attached to the shaft 93 and carries contact pieces 105, on which a contact 112 is sliding. The shaft is connected by wires over an electric battery 114 to a coil 113 and back to the contact 112. The pieces 105 are directly connected to the shaft 93.

The light source 5 and the condenser lenses 93 and 100 are arranged for lighting the film 1. The light passes successively the film 1, the square 83, the mirror 88, the lens-system 2, the mirror 87, the cube 84 and reaches the film 13. In order to cut off all disturbing and scattered light, the diaphragm 85 and the tubes 86 are provided, which protect the lens 2 and the film 13 against very inclined light. The fact that the two inner mirrors of the square 83 and the cube 84 are shorter than the other mirrors and only as great as is necessary for getting complete images, serves for the same purpose. By such an arrangement of diaphragms, which cut off, all devices according to the invention may be im- 23

proved as the purity of colors and the glance of the duplicate images is augmented.

The optical cube 84 is formed by three plane surfaces, which are perpendicular to each other.

5 It serves for interchanging the top and the bottom of the printed image, so that this is correct with respect to right and left and that the films may be pulled in the same and not in opposite directions. The square 83 and the cube 84

10 may be interchanged or the cube may be replaced by a square and one of the mirrors 87, 88 replaced by an optical square with horizontal edge. But it is most preferable to use an optical cube, as on the sliding-carriage is more free

15 place for arranging such means than near the lens.

Within the lens-system 2 a diaphragm 10 is arranged, which has a point-shaped aperture. It was told already with respect to Figure 11,

20 that the aperture may be slit- or point-shaped. But the point-shaped aperture renders better images on the duplicate film, as the lens must image at the same time the layer of the film 1 on the layer of the film 13 and the lenticulation

25 of the film 1 on the lenticulation of the film 13. This is only possible with a lens-system of very small aperture.

A shutter 89 is arranged within the lens system 2. It is actuated by the coil 113 when the

30 contact 112 touches one of the pieces 105. Thus only the centers of all stripes on the photographic layer are copied. The number of the contact pieces 105 is equal to the number of different stripes behind one lenticular element.

35 The manner of working of this machine may be easily understood by the Figure 18, which was described already. The ordinates are then the distances of the sliding-carriage from its end-position.

40 It is understood that the mechanical equipment of the described apparatus may be altered in many respects. The pull-down mechanism for the films, the shutter, the driving mechanism for the oscillating optical means may be replaced

45 by other means without touching the optical principle of the machine.

An advantage resulting from the special optical arrangement is that there result nearly no defects, when the guiding of the oscillating carriage is afflicted with small inaccuracies—which, it is true, must only be small. The most important condition that must be fulfilled is that the optical squares or the optical square and cube are exactly adjusted with respect to each other. When, in this case, the carriage vibrates a little, no fault can be observed, as the film 1 is always correctly imaged to the film 13, provided that the fixed arranged optical means are exactly adjusted.

60 Another important advantage is that the light rays run from the original to the duplicate film completely on one side of the plane which is given by the film-gates. It may easily be seen that the arrangement of the optical means allows

65 to copy also films on which the cylindrical lenticular elements are inclined with respect to the longitudinal direction of the films or perpendicular to this direction.

70 It is even possible to employ films for the original and the duplicate, on which the lenticulations are inclined by different angles. One may, for instance, employ as original a longitudinally and as duplicate a transversely goffered film.

75 But such copying processes can only be performed,

when there is room enough for guiding the films without breaking them.

The described machine allows to guide the films nearly in any desired direction. Besides there is room enough for attaching a big lightening device comprising an intensive light-source and a special condenser optic. These are necessary as the small lens aperture allows only narrow light beams to pass. Moreover the intensive light-source must be cooled, so that much room is afforded.

Some manners of guiding the films are shown in the Figures 18 through 22. These figures correspond to the Figure 16. The optical principle of these modifications is the following: The image of the lens-aperture seen from the films is oscillating in a direction parallel to the straight connection of the centers of the gates. This direction is indicated by the straight line 108. Consequently the directions of the lenticular elements 20 may not freely be chosen. Certainly, they must not run in parallel to the line 108. But it is allowed that they form an angle with this direction which is great enough, without necessarily being

25 a right angle.

Let us suppose the angle between the line 108 and the lenticular elements to be different from zero and 90°. Then the amplitude of the oscillations of the lens-image must be so great that the angle by which it is seen from the films is 30 equal about to the relative aperture of the lenticular elements divided by the sine of said angle. Thus this angle must not differ too much from 90° as the focal length of the lens and the greatness of the corrected image field do not allow 35 too great amplitudes.

Further, when the relative apertures of the lenticular elements on the original and the duplicate film are equal, the angles between the line 108 and the cylindrical element must be equal 40 for both films. If the relative apertures differ, the sines of the said angles must be proportionate to the relative apertures. But it is still possible that the angles are taken in the same or in opposite directions, so that the images of the 45 original lenticulations projected on the duplicate film are running in parallel to the duplicate lenticulations or are inclined to them.

When the optical equipment of the printing machine is exactly identical with that represented in the Figures 15, 16 and 17—so that upright prints are obtained, the film gates must be parallel to each other. This is the case in the devices according to Figures 16, 19, 21 and 22. When the optical cube is replaced by an optical square—so 55 that the bottom and the top of the images are interchanged, the film-gates are symmetrically inclined with respect to the line 108, as is drawn in the Figures 20 and 23. As in the Figures 19 through 23 the hatching indicates the directions 60 of the lenticular-elements, from the aforesaid meditations results that the images of the lenticulations of the original are parallel to the lenticulations of the duplicate in the device of the Figure 19 only, while in the devices of the Figures 20 through 23 the said directions are crossed. The device of Figure 16 may be used for films, on which the lenticulations form any angle with the direction of the film, when this angle is not too great and the conditions enumerated above are fulfilled.

In the device of Figure 19 the lenticular elements are transverse to the films. The films are slightly inclined with respect to the line 108, so that they can be guided without being broken.

The lenticulations of the films 55b and 55c of 75

Figures 20 and 21 are transverse, while the films 56b and 56c are longitudinally lenticulated. The angles between the films and the line 408 are 45 degrees. These machines are of special importance as they allow to copy longitudinally and transversely lenticulated films in any combination without touching to the optical equipment, only the guidings and the film-gates being altered.

The device according to Figure 22 serves for employing two longitudinally lenticulated films and for arranging the images slantwise on the duplicate.

The device according to Figure 23 serves for employing one film which is longitudinally and one which is obliquely lenticulated. The duplicates 56d and 56e have the advantage, that the oblique running lenticulations are less striking than horizontally or vertically running lenticulations.

20 The optical principle of the machine, which is represented in Figure 24 is somewhat different from that which was described by the help of the Figures 14 through 23. The oscillating body 66 has two reflecting surfaces 65 and 65' forming a right angle with each other. They are reflecting on both sides.

The light coming from the original film is reflected by the surface 65', by the totally reflecting prism 67, by the mirror 65, by the mirror 68 inclined by 22½ degrees and reaches the lens 2. Near this lens the shutter 68 is arranged. This shutter is represented in Figure 25 and was described already. After passing the lens the light meets the mirror 69, equally inclined by 22½ degrees, and is then reflected by the mirrors 65, 65' and 70. At last it reaches the duplicate film 13. The glass-block 82 serves for making the optical distances from the lens to the films identic with each other. The body 66 is swinging in the 40 direction of the double-arrow, as is indicated by the dotted lines.

Nearly all the described devices are symmetrical so that the films may be interchanged and the direction of light inverted. But this must not be so. For the condition is, that the lens aperture is seen from the films at the same distances as the filter is seen in the taking or projecting process. In order to fulfil this condition lenses of suitable curvature may be arranged 50 near the films. As the filters may have different distances in the taking and projecting process, either the said lenses must be differently curved or the printing lens must be unsymmetrical. At last it is sometimes necessary to change the scale 55 of the images by the printing process, which too necessitates an unsymmetrical arrangement.

I claim:

1. In combination, an original film having thereon a multiplicity of lenticulations and a group of color records behind each of said lenticulations, a copy film having similar lenticulations thereon, means for passing light through the original film to the copy film, an optical system disposed in the path of light passing between 60 said films and including a non-reversing mirror, and means causing relative movement between said films and portions of said system, said movement being many times as great as the width of one of said lenticulations, thereby substantially increasing the angle of a beam of light leaving or reaching each of said lenticulations.

2. In combination, an original film having thereon a multiplicity of lenticulations and a group of color records behind each of said 75 lenticulations, a copy film having similar lenticu-

lations thereon for passing light through the original film to the copy film, a lens disposed in the path of light passing between said films, optical means causing said lens to be seen from the lenticulations of the original film in a plurality of different directions, optical means likewise causing said lens to be seen from the lenticulations of the copy film in a plurality of different directions, means for feeding said films, and a shutter having blades adapted to interrupt said light at such time as to avoid exposure of the dividing line between said records.

3. In combination, an original film having thereon a multiplicity of lenticulations and a group of color records behind each of said lenticulations, a copy film having similar lenticulations thereon, means for simultaneously passing light through all the color records of the original film to the copy film, an optical system disposed in the path of light passing between said films, 20 means for relatively moving said films and portions of said system to an extent many times greater than the width of one of said lenticulations, thereby substantially increasing the angle of a beam of light leaving or reaching each of 25 said lenticulations, and diaphragms arranged parallel to the path followed by the light to said optical system and arranged to prevent diffused or scattered light from reaching the copy film.

4. In combination, a film having thereon a multiplicity of lenticulations of substantially equal aperture, a lens of smaller aperture than that of a lenticulation and through which lens and said lenticulations light may pass, and optical means arranged, with respect to said lens and to said lenticulations, to cause said lens to be seen, from a lenticulation, simultaneously in a plurality of different definite directions and in certain definite positions with respect to each other and to said lenticulation, to virtually increase the aperture of said lens to substantially equal the aperture of a lenticulation.

5. In combination, a film having thereon a multiplicity of lenticulations of substantially equal aperture, a lens of smaller aperture than that of a lenticulation and through which lens and said lenticulations light may pass, and optical means arranged, with respect to said lens and to said lenticulations, to form images of said lens and to cause said lens and said images to be seen, from a lenticulation, simultaneously in a plurality of different definite directions and in certain definite positions with respect to each other and to said lenticulation, to virtually increase the aperture of said lens to substantially equal the aperture of a lenticulation.

6. In combination, a film having thereon a multiplicity of lenticulations of substantially equal aperture, a lens of smaller aperture than that of a lenticulation and through which lens and said lenticulations light may pass, and optical means arranged, with respect to said lens and to said lenticulations, to form images of said lens and to cause said images to be seen, from a lenticulation, simultaneously in a plurality of different 65 definite directions and in certain definite positions with respect to each other and to said lenticulation, to virtually increase the aperture of said lens to substantially equal the aperture of a lenticulation.

7. In combination, a film having thereon a multiplicity of lenticulations of substantially equal aperture, a lens of smaller aperture than that of a lenticulation and through which lens and said lenticulations light may pass, and optical 75

means arranged, with respect to said lens and to said lenticulations, and on opposite sides of said lens transversely of said lenticulation, to virtually increase the aperture of said lens to substantially equal the aperture of a lenticulation.

8. In combination, a film having thereon a multiplicity of lenticulations of substantially equal aperture, a lens of smaller aperture than that of a lenticulation and through which lens and said lenticulations light may pass, and mirrors disposed generally parallel to the optical axis of said lens and arranged, laterally with respect to said lens and transversely with respect to said lenticulations, to form images of said lens and to cause said images to be seen, from a lenticulation, simultaneously in a plurality of different definite directions and in certain definite positions with respect to each other and to said lenticulation, to virtually increase the aperture of said lens to substantially equal the aperture of a lenticulation.

9. In combination, a film having thereon a multiplicity of lenticulations of substantially equal aperture, a lens of smaller aperture than that of a lenticulation and through which lens and said lenticulations light may pass, mirrors disposed generally parallel to the optical axis of said lens and arranged, laterally with respect to said lens and transversely with respect to said lenticulations, to form images of said lens and to cause said images to be seen, from a lenticulation, simultaneously in a plurality of different definite directions and in certain definite positions with respect to each other and to said lenticulation, to virtually increase the aperture of said lens to substantially equal the aperture of a lenticulation, and diaphragms disposed between said mirrors and arranged to limit the number of images thus seen at a lenticulation, by intercepting light in excess of that needed to form said number of images.

10. In combination, a film having thereon a multiplicity of lenticulations of substantially equal aperture, a lens of smaller aperture than that of a lenticulation and through which lens and said lenticulations light may pass, mirrors disposed generally parallel to the optical axis of said lens and arranged, laterally with respect to said lens and transversely with respect to said lenticulations, to form images of said lens and to cause said images to be seen, from a lenticulation, simultaneously in a plurality of different definite directions and in certain definite positions with respect to each other and to said lenticulation, to virtually increase the aperture of said lens to substantially equal the aperture of a lenticulation, and diaphragms disposed between said mirrors and arranged to limit the number of images thus seen at a lenticulation, by intercepting light in excess of that needed to form said number of images, said film being adapted to be used with a color filter having a plurality of zones, and said number of images being the same as the number of said zones.

11. In combination, a film having thereon a multiplicity of lenticulations of substantially equal aperture, said lenticulations being adapted to be used with a plural-zoned color filter to form a plurality of color records behind each lenticulation, a lens of smaller aperture than that of a lenticulation and through which lens and said lenticulations light may pass, and optical means arranged, with respect to said lens and to said lenticulations, to cause said lens to be seen, from a lenticulation, simultaneously in different defi-

nite directions and positions equal in number to the number of color records behind a lenticulation and having the same relation to each other.

12. In combination, a film having thereon a multiplicity of lenticulations of substantially equal aperture, said lenticulations being adapted to be used with a plural-zoned color filter having zones of substantially equal aperture, to form a plurality of color records behind each lenticulation, a lens of smaller aperture than that of a lenticulation and through which lens and said lenticulations light may pass, and optical means arranged, with respect to said lens and to said lenticulations, to cause said lens and images thereof to be seen, from a lenticulation, simultaneously in different definite directions and positions equal in number to the number of color records behind a lenticulation, said lens aperture and the aperture of each image being substantially equal to each other and to the aperture of a color zone of the filter.

13. In combination, a film having thereon a multiplicity of lenticulations of substantially equal aperture, said lenticulations being adapted to be used with a plural-zoned color filter to form a plurality of color records behind each lenticulation, a lens of smaller aperture than that of a lenticulation and through which lens and said lenticulations light may pass, optical means arranged, with respect to said lens and to said lenticulations, to cause said lens to be seen, from a lenticulation, simultaneously in different definite directions and positions equal in number to the number of color records behind a lenticulation and having the same relation to each other, and a diaphragm associated with said lens to cut the adjacent margins of the lens and its images as thus seen from a lenticulation.

14. In combination, a film having thereon a multiplicity of lenticulations of substantially equal aperture, a lens of smaller aperture than that of a lenticulation and through which lens and said lenticulations light may pass, optical means arranged, with respect to said lens and to said lenticulations, to cause said lens to be seen, from a lenticulation, simultaneously in a plurality of different definite directions and in certain definite positions with respect to each other and to said lenticulation, to virtually increase the aperture of said lens to substantially equal the aperture of a lenticulation, and means providing a separation between the views of said lens as thus seen from a lenticulation.

15. In combination, an original film having thereon a multiplicity of lenticulations and a group of color records behind each lenticulation, a copy film having similar lenticulations thereon, an optical system adapted to transmit light from the original film to the copy film and including a lens of smaller aperture than that of a lenticulation, and optical means arranged, with respect to said lens and films, to cause said lens to be seen, from a lenticulation on either film, simultaneously in a plurality of different definite directions and in certain definite positions with respect to each other and to said lenticulation, to virtually increase the aperture of said lens to substantially equal the aperture of a lenticulation.

16. In combination, an original film having thereon a multiplicity of lenticulations and a group of color records behind each lenticulation, a copy film having similar lenticulations thereon, an optical system adapted to transmit light from the original film to the copy film and including

- a lens of smaller aperture than that of a lenticulation, and optical means arranged, with respect to said lens and films, to form images of said lens and to cause said lens and said images to be seen, from a lenticulation on either film, simultaneously in a plurality of different definite directions and in certain definite positions with respect to each other and to said lenticulation, to virtually increase the aperture of said lens to substantially equal the aperture of a lenticulation. 10
17. In combination, an original film having thereon a multiplicity of lenticulations and a group of color records behind each lenticulation, a copy film having similar lenticulations thereon, an optical system adapted to transmit light from the original film to the copy film and including a lens of smaller aperture than that of a lenticulation, means for feeding both films at substantially the same rate past respective positions 15 wherein said optical system may thus transmit light from the original to the copy film; and optical means, acting while the same respective areas of the two films are at said respective positions, to cause said lens to be seen, from a lenticulation on either film, in a plurality of different definite directions and in certain definite positions with respect to each other and to said lenticulation, to virtually increase the aperture of said lens to substantially equal the aperture 20 of a lenticulation. 25
18. In combination, an original film having thereon a multiplicity of lenticulations and a group of color records behind each lenticulation, a copy film having similar lenticulations thereon, an optical system adapted to transmit light from the original film to the copy film and including a lens of smaller aperture than that of a lenticulation, means for intermittently feeding both films past respective positions wherein said optical system may thus transmit light from the original to the copy film, and optical means acting between feeding movements of the films to cause said lens to be seen, from a lenticulation on either film, in a plurality of different definite directions and in certain definite positions with respect to each other and to said lenticulation, to virtually increase the aperture of said lens to substantially equal the aperture of a lenticulation. 30
19. In combination, an original film having thereon a multiplicity of lenticulations and a group of color records behind each lenticulation, a copy film having similar lenticulations thereon, an optical system adapted to transmit light from the original film to the copy film and including a lens of smaller aperture than that of a lenticulation, means for intermittently feeding both films past respective positions wherein said optical system may thus transmit light from the original to the copy film, and optical means acting between feeding movements of the films to cause said lens to be seen, from a lenticulation on either film, in a plurality of different and definite directions and positions equal in number to the number of color records behind a lenticulation and having the same relation to each other. 35
20. In combination, an original film having thereon a multiplicity of lenticulations and a group of color records behind each lenticulation, a copy film having similar lenticulations thereon, an optical system adapted to transmit light from the original film to the copy film and including a lens of smaller aperture than that of a lenticulation, means for feeding both films at substantially the same rate past respective positions 40 wherein said optical system may thus transmit light from the original to the copy film, and optical means operating while the films are at said respective positions for moving said films and a part of said optical system relatively to each other, transversely of the optical axis of said system and of the lenticulations, to an extent many times greater than the width of a lenticulation, to virtually increase the aperture of said lens to substantially equal the aperture of a lenticulation and to form a group of color records behind each 45 lenticulation on the copy film. 50
21. In combination, an original film having thereon a multiplicity of lenticulations and a group of color records behind each lenticulation, a copy film having similar lenticulations thereon, an optical system adapted to transmit light from the original film to the copy film and including a lens of smaller aperture than that of a lenticulation, means for feeding both films at substantially the same rate past respective positions 55 wherein said optical system may thus transmit light from the original to the copy film, and means operating while the films are at said respective positions for moving said films and a part of said optical system relatively to each other, transversely of the optical axis of said system and of the lenticulations, to an extent sufficient to cause said lens to be seen from a lenticulation of either film in a plurality of positions corresponding, in number and relation to each other, to the records behind a lenticulation of the original film. 60
22. In combination, an original film having thereon a multiplicity of lenticulations and a group of color records behind each lenticulation formed by exposure through a plural-zoned color filter, a copy film having similar lenticulations thereon, an optical system adapted to transmit light from the original to the copy film and including a lens of smaller aperture than that of a lenticulation, means for feeding both films at substantially the same rate past respective positions 65 wherein said optical system may thus transmit light from the original to the copy film, and means operating while the films are at said respective positions for moving said films and a part of said optical system relatively to each other, transversely of the optical axis of said system and of the lenticulations, to an extent sufficient to cause said lens to be seen from a lenticulation of the copy film in a plurality of positions having the same angular relation to each other as the corresponding zones of the taking color filter bore to a lenticulation of the original film during taking. 70
23. In combination, an original film having thereon a multiplicity of lenticulations and a group of color records behind each lenticulation, a copy film having similar lenticulations thereon, an optical system adapted to transmit light from the original film to the copy film and including a lens of smaller aperture than that of a lenticulation, means for intermittently feeding both films past respective positions wherein said optical system may thus transmit light from the original to the copy film, optical means acting between feeding movements of the films to cause said lens to be seen, from a lenticulation on either film, in a plurality of different and definite directions and positions equal in number to the number of color records behind a lenticulation and having the same relation to each other, and a shutter having blades adapted to interrupt said light at such time as to avoid exposure of the dividing line between said records. 75

24. In combination, an original film having thereon a multiplicity of lenticulations and a group of color records behind each lenticulation, a copy film having similar lenticulations thereon, an optical system adapted to transmit light from the original film to the copy film and including a lens of smaller aperture than that of a lenticulation, and plane mirrors arranged on opposite sides of the lens and lengthwise of the lenticulations of both films, and adapted to cause said lens to be seen, from a lenticulation on either film, simultaneously in a plurality of different definite directions and in certain definite positions with respect to each other and to said lenticulation, to virtually increase the aperture of said lens to substantially equal the aperture of a lenticulation.
25. In combination, an original film having thereon a multiplicity of lenticulations and a group of color records behind each lenticulation, a copy film having similar lenticulations thereon, an optical system adapted to transmit light from the original film to the copy film and including a lens of smaller aperture than that of a lenticulation, and optical means arranged, with respect to said lens and films, to cause said lens to be seen, from a lenticulation on either film, simultaneously in a plurality of different definite directions and in certain definite positions with

respect to each other and to said lenticulation, to virtually increase the aperture of said lens to substantially equal the aperture of a lenticulation, said films both being on the same side of the lens and the light passing from the original film through the lens, and said system including means to reflect the light back through the lens to the copy film.

26. In combination, an original film having thereon a multiplicity of lenticulations and a group of color records behind each lenticulation, a copy film having similar lenticulations thereon, an optical system adapted to transmit light from the original film to the copy film and including a lens of smaller aperture than that of a lenticulation, and optical means arranged, with respect to said lens and films, to cause said lens to be seen, from a lenticulation on either film, simultaneously in a plurality of different definite directions and in certain definite positions with respect to each other and to said lenticulation, to virtually increase the aperture of said lens to substantially equal the aperture of a lenticulation, the path of light between said films being substantially confined to a glass block having the elements of the optical system substantially a part thereof.
